(57) **CLAIM**

The ornamental design for a segmented cooked dough food product, as shown and described.

DESCRIPTION

FIG. 1 is a perspective view of a segmented cooked dough food product that is generally rectangular in plan view and further characterized as being divided into product halves by a segment line and as being divided into an odd number of plural product portions by crossing segment lines, the product shown with six segments having surface slits;

FIG. 2 is a front plan view of the segmented cooked dough food product of FIG. 1;

FIG. 3 is a left side view of the segmented cooked dough food product of FIG. 1;

FIG. 4 is a top end view of the segmented cooked dough food product of FIG. 1;

FIG. 5 is a bottom end view of the segmented cooked dough food product of FIG. 1;

FIG. 6 is a right side view of the segmented cooked dough food product of FIG. 1;

FIG. 7 is a back view of the segmented cooked dough food product of FIG. 1, the dashed lines indicating lines of weakening shown as perforations;

FIG. 8 is a perspective view of a segmented cooked dough food product similar to FIG. 1 but without surface slits; and FIG. 9 is a front plan view of the segmented cooked dough food product of FIG. 8;

FIG. 10 is a left side view of the segmented cooked dough food product of FIG. 8;

FIG. 11 is a top end view of the segmented cooked dough food product of FIG. 8;

FIG. 12 is a bottom end view of the segmented cooked dough food product of FIG. 8;

FIG. 13 is a right side view of the segmented cooked dough food product of FIG. 8;

FIG. 14 is a back view of the segmented cooked dough food product of FIG. 8, the dashed lines indicating lines of weakening shown as perforations;

FIG. 15 is a perspective view of a segmented cooked dough food product that is generally rectangular in plan view and further characterized as being divided into product halves by a segment line and as being divided into an odd number of plural product portions by crossing segment lines, the product shown with ten segments having surface slits;

FIG. 16 is a front plan view of the segmented cooked dough food product of FIG. 15;

FIG. 17 is a left side view of the segmented cooked dough food product of FIG. 15;

FIG. 18 is a top end view of the segmented cooked dough food product of FIG. 15;

FIG. 19 is a bottom end view of the segmented cooked dough food product of FIG. 15;

FIG. 20 is a right side view of the segmented cooked dough food product of FIG. 15; and,

FIG. 21 is a back view of the segmented cooked dough food product of FIG. 15, the lines indicating lines of weakening.
